CLIFTON W. NIXON, OF NEW YORK, N. Y.

CONTROLLING MECHANISM FOR DISPENSING MACHINES

Application filed July 11, 1928, Serial No. 291,824, and in Great Britain July 13, 1927.

This invention relates to article dispensing machines and is illustrated as embodied in a combined vending and change-making machine wherein a coin-controlled carrier is arranged to constitute a transmission connector between the operating mechanism and the power receiving means by the agency of which articles are discharged from the machine, the invention being more particularly related to an arrangement including an automatic control for putting the transmission connector out of operative relationship with its operating mechanism at a predetermined place.

15 The invention has for its paramount object to preclude absolutely the surreptitious operation of the working parts of the machine by providing means for automatically transferring the operative control of the 20 working parts from the operator to mechanically operated means.

More specifically, the invention comprises a mechanical organization in which hand-actuated mechanism is arranged to control the 25 operation of the transmission connector, and in which tripping or disconnecting means, preferably arranged under the control of the transmission connector, is provided for completely separating the operative connection 30 between the hand actuated mechanism and the transmission connector.

Another object of the invention is the provision in a machine where the transmission connector is completely and automatically 35 separated at one point from its power receiving means, of tripping or disconnecting means of the character described which is arranged to effect the separation of the hand-actuated mechanism from the transmission connector prior to the separation of the power receiving means from the transmission connector.

It is to be understood that in illustrating a particular form of my invention as embodied 45 in a combined vending and change-making machine adapted to sell merchandise and give change, I have not intended to limit the broader aspects of the invention to that particular type of machine; for my present invention involves principles of general appli-

cation which may be variously adapted and modified for use in connection with a machine for making change only, or in connection with a machine for vending merchandise only.

The subject matter of the present invention is, in a general way, also described in and certain novel features of the invention herein described, but not herein claimed, are claimed in my two contemporaneously pending applications, both filed June 7, 1927, and bearing Serial No. 197,075, and Serial No. 197,076, respectively. The specific hand-actuated mechanism herein described, but not herein claimed, comprises certain improvements over my application No. 197,076 aforesaid and said mechanism is more fully illustrated and described in the contemporaneously pending application of Louis H. Larsen and Samuel C. McKeown, filed April 2, 1928, Serial No. 266,798.

Other objects will appear hereinafter.

The invention consists in the details of construction and in the arrangement and combination of parts hereinafter described and claimed.

The invention will be best understood by reference to the accompanying drawings forming a part of this specification, and in which:—

Fig. 1 represents a fragmentary vertical sectional view through a combined vending and change-making machine, showing the adaptation therewith of an automatic control in accordance with this invention;

Fig. 2 represents a top plan view of the coin-controlled carrier which constitutes the transmission connector;

Fig. 3 represents a side elevation and section of the coin-controlled carrier and means commanded thereby for effecting the separation of the operative connection between the hand-actuated mechanism and said carrier, the parts here being shown as they appear at the moment of effecting such separation;

Fig. 4 represents a horizontal cross-section, taken on the line 4—4 of Fig. 3;

Fig. 5 represents a fragmentary sectional plan view on a larger scale taken on the line 5—5 of Fig. 3; and

Fig. 6 represents a fragmentary view partially in section, showing the co-operating draw-bar and pull-bar parts.

The combined vending and change-making machine, illustrated in the accompanying drawings and in which I have shown an embodiment of my invention as a preferred example, comprises a casing 10 and a skeleton magazine structure 11 mounted for rotation therein and composed of a circular lower section 12, a circular upper section 13, and vertically extending rods 14 rigidly connecting said sections. The lower section 12 is supported for rotation upon a suitable axis shaft 15, while the upper section 13 is supported for rotation with a suitable axis shaft 16. Fixed to the lower section 12 is a ring plate 17 on which are mounted a circular series of upright holding units 18 for containing the merchandise to be sold; and fixed to the upper section 13 is a ring plate 19 carrying a corresponding circular series of change-holding units 20, each composed of a plurality of wells 21 for containing the change to accompany the merchandise to be sold. The upper ring plate 19 has secured thereto an internal gear 22 with which is engaged a driving pinion 23 operated through shaft 24, bevel gears 25, stud shaft 26 and sliding connections 27 from a hand-actuated element in the form of a handle 28 arranged for rotation in a bearing block 29. By turning the handle 28, the magazine structure can be turned so as to bring any desired merchandise holding unit 18 with its accompanying change-holding unit 20 into delivery position with relation to the delivery receptacle 30.

The machine may be provided with a plurality of power receiving devices in the form of suitable bell crank actuators 31, of which in the present instance there are three (see Fig. 4), each mounted upon a horizontal pin 32 for partial rotation toward the front 33 of the casing so as to command the operation of coin ejectors as 34 adapted to eject coins from the wells of the change-holding units 20. The short arm of each bell crank actuator engages under a coiled cushioning spring 35 carried by a lift frame 36 including side members 37 formed with ears 38 mounted to turn on the horizontal pin 32, said side members 37 suitably converging as shown to provide parallel ends 39 arranged on opposite sides of the axis shaft 16 for the support thereon of a lift sleeve 40. Pinned at 41 to the lift sleeve 40 is a lift shaft 42 telescoping within the axis shaft 16 and connected at its lower end by a ball and socket joint 43 with a lift rod 44, there being provided on the lift shaft 42 a hollow cylindrical weight 45 which surrounds the ball and socket joint and which serves as a medium, through the agency of lift shaft 42, lift sleeve 40 and lift frame 36, for maintaining the bell crank actuators 31 in starting position as well as for reposition-

ing the same after each actuation toward the casing front 33. A bell crank 46 is pivoted at one end to the lower end of lift rod 44 and at its other end to a push rod 47 having pivotal connection with a master pusher 48. With this construction, each bell crank actuator controls the operation of the master pusher 48. Each merchandise holding unit 18 is furnished with a merchandise ejector 49, and when a holding unit is brought into delivery position behind the delivery receptacle 30, its ejector 49 is aligned with the master pusher 48 to be operated thereby for the discharge of merchandise into the delivery receptacle. Therefore, on each operation of each bell crank actuator, it is possible to effect the discharge of merchandise and change.

The bearing block 29 is supported solely by a fulcrum pin 50 on the frame 51 so that the handle 28 can be moved downwardly or depressed with the bearing block turning on the fulcrum pin 50 for the purpose of providing power for advancing inwardly of the casing away from the front wall 33 thereof

80 a transmission connector in the form of a bodily movable carrier 52, this operation being accomplished through the agency of a train of parts comprising a bell crank 53, link 54, and draw-bar 55 adapted to be engaged with a pull-bar 56 which is pivotally attached to the carrier 52. For each bell

85 crank actuator 31, there is provided on the carrier a coin-controlled unit 57 commanding a hooked catch-bar 58 adapted, when the carrier is advanced to extreme position from the casing front 33, to be engaged with the hooked end 59 of its corresponding bell crank actuator so as to operate the same and effect

90 a discharge of merchandise and change as the carrier is returned toward the casing front 33.

100

105

As above noted, there are, in the present instance, three coin-controlled units 57, one for each bell crank actuator. As will be observed from an inspection of Fig. 2, the carrier includes elongated strips 60, 61 and 62 connected by cross pieces 63 and 64 provided with shoes 65 adapted to slide on guides or rails 66. Coiled pull springs 67 connect

110 projections 68 on the strips 60 and 62 with fixed projections 69 adjacent the casing front, whereby the carrier is retracted against an abutment block 70. With each of the strips 60, 61 and 62, is associated a coin holding unit 57 including a head 71 and slide 72 forming a coin-space 73. The coin-spaces may differ in size to accommodate different sizes of coins. The slides 72 have movement relatively to their heads, being provided with pins

115 74 slidable in elongated slots 75 provided in their associated strips. By springs 76, connecting the pins 74 with pins 77 on the strips, the slides are drawn toward their heads to clamp coins in the coin-spaces. To adjust

120 the slides and make the coin-spaces of proper

125 130

coin receiving size as the carrier is retracted against the abutment block, suitable pins 78 project laterally from the slides so as to engage adjustable stop pins 79 depending from the supporting frame 80. As the carrier advances from the abutment block, the tensioned slides clamp any coins reposing in the coin-spaces.

When, in operation, a slide 72 clamps a coin in the coin-space against its cooperating head 71, it is thereby rendered effective, upon the carrier being drawn to extreme position from the casing front 33, to engage its catch-bar 58 with the hook 59 of the corresponding bell crank actuator, so that upon the retiring movement of the carrier toward the casing front 33, the engaged bell crank actuator will also be drawn toward the casing front 33 to effect a discharge of merchandise and change.

Where there is no coin clamped in the coin-space, a slide will not be connected up with its bell crank actuator, its catch-bar 58 falling short of engagement with the hooked end 59 thereof, since the spring 76 on the disengagement of the pin 78 with the stop 79 draws the slide toward the casing front 33 to the full extent permitted by the slot 75. Momentarily prior to the return of the carrier to its position of rest against the abutment block 70 and after the merchandise and change have been discharged, the engaged bell crank actuator 31 is released for its movement to starting position because of the engagement of a trip pin 82.

In order to put the returning movement of the carrier toward the casing front 33 positively beyond the control of the handle 28 and under the control of the retractile springs 67, it is necessary completely to separate the transmission connections comprising the draw-bar 55 and pull-bar 56. If with a catch-bar 58 engaged with a bell crank actuator 31, the handle be operated up and down without bringing it fully to that precise position where such engaged catch-bar 58 will be tripped from its coengaged bell crank actuator 31, all of the goods in a merchandise holding unit 18 and as well all of the change in the companion change-holding unit 20 can be discharged from the machine without the deposit of purchase coins. In the preferred embodiment of my invention, the draw-bar 55 and pull-bar 56 are made so as to establish automatically an interlocking engagement on the initial down stroke of the handle 28 and so as to have such interlocking engagement disestablished on the initial up stroke thereof. For this purpose, as best shown in Fig. 6, the draw-bar 55 is made with a yoked end to provide spaced arms 83 and 83' between which is secured a cylindrical body 84 having a hook receiving notch 85, while the pull-bar 56 has a relatively long neck 86 terminating in a cam hook 87. With the parts in posi-

tion to be operated as shown in Fig. 1 the neck 86 is situated between the arms 83 and 83' with the hook in position to be engaged in the notch 85 on slight movement of the draw-bar, which moves upwardly and rearwardly on an arc, it being mounted to swing on a pivot pin 88 on the frame 51. The pull-bar is positioned for interlocking engagement with the draw-bar by means of a contact ledge 89 fixed thereto, which contact ledge is adapted to engage an elongated block 90 and slide to the top of an upwardly projecting cam portion 91 thereon, as the carrier comes to rest against the abutment block.

The means for separating the draw-bar 55 and pull-bar 56 comprises a tripping device in the form of a kick up pin 92 provided eccentrically on a disk-shaped base 93 which is placed upon an annular flange 94 produced for the purpose on the upper end of the lift sleeve 40. This kick up pin is slidably fitted in a vertical tubular guide 95 secured in a suitable frame part 96, and it is held against rotation by a key 96 having sliding fit in a key way 98 therein, said key being suitably fixed to the frame part 96 and passing laterally into the guide 95. At its top end, the kick up pin is furnished with a roller 99 adapted to impinge and turn on, the contact ledge 89. These parts are so arranged and proportioned that when the carrier is in extreme position from the casing front 33, the roller 99 will be in close proximity to the underface of the contact ledge 89 where only a slight upward movement of the sleeve and kick up pin, impelled by one of the bell crank actuators, will force the pull-bar upwardly, lifting the hook 87 completely from the notched body 84 of the draw-bar, it being observed in this connection that the pull-bar is attached by a pivot pin 100 to the central strip 61 so as to have free vertical movement. This action takes place on slight upward movement of the handle from its lower terminal of movement, and it will be evident that immediately the hook 87 is raised from the notched body 84, the retractile springs 67 will function to complete the retiring movement of the carrier to the abutment block. In this way, the carrier, any bell crank actuator engaged therewith, and consequently all working parts controlling the merchandise and coin ejectors, are placed beyond the control of the operator of the machine at the beginning of the return stroke of the carrier. In Fig. 3

I illustrate the relative positions of the parts at the moment the pull-bar is forced out of engagement with the draw-bar. The retractile springs 67 draw the carrier to its position of rest against the abutment block 70 before the handle can be moved upwardly into its elevated terminal position. As a result, the pull-bar 56 is positioned upon the cam portion 91 when the returning draw-bar engages its cylindrical body 84 with the cam hook 87,

whereby the pull-bar is moved upwardly to admit the notched body 84 behind the hook 87 in position for interlocking engagement on the initial down stroke of the handle.

5 It will be apparent from what has been said that I have provided a novel and useful construction of controlling mechanism which embodies the features of advantage enumerated in the statement of invention and the 10 above description, and while I have, in the present instance, shown and described a specific form of mechanism embodying the principle of my invention, it is to be understood that this is susceptible of modification in various 15 particulars without departing from the spirit and scope of my invention or sacrificing any of its advantages.

Having thus described my invention, what I claim is:

20 1. In a machine of the character described, an actuating mechanism, a transmission connector in the form of a carrier, means affording a separable connection for operating said carrier by said mechanism, and means dependent for its action upon the operation of 25 said carrier for separating said separable connection whereby entirely to release said carrier from the control of said mechanism.

2. In a machine of the character described, 30 an actuating mechanism, a carrier with retractile means acting thereon arranged to be connected to said mechanism to be operated thereby against the force of the retractile means, and means for disconnecting said carrier from said mechanism to place the former under the sole control of its retractile means.

3. In a machine of the character described, 35 an actuating mechanism, a power receiving lever, a carrier with retractile means acting thereon arranged to operate said power receiving lever and to be connected to said mechanism to be operated thereby against the force of the retractile means, and means for disconnecting said carrier from said mechanism to put the operation of said power receiving lever under the sole control of said carrier.

4. In a machine of the character described, 40 an actuating mechanism, a carrier, means comprising a pair of pivoted co-acting members arranged to afford a separable connection for operating said carrier by said mechanism, and means controlled by said carrier controlling the separation of said co-acting members during the conjoint operation of said mechanism and carrier.

5. In a machine of the character described, 45 the combination of actuating mechanism, a transmission connector, two members, one comprising a pull-bar attached to said connector and the other comprising a draw-bar attached to said mechanism, said members being arranged for interlocking engagement 50 whereby to move said connector by said mech-

anism, and means for forcing said members out of interlocking engagement.

6. In a machine of the character described, 55 the combination of actuating mechanism, a transmission connector, two members, one comprising a pull-bar attached to said connector and the other comprising a draw-bar attached to said mechanism, said members being arranged for interlocking engagement for moving said connector by said mechanism, 60 means for tripping the pull-bar member out of interlocking engagement with the draw-bar member, and means under the control of said connector controlling the actuation of said tripping means.

7. In a machine of the character described, 65 the combination with a movably mounted spring retracted carrier including a pull-bar, of a hand-actuated mechanism including a draw-bar capable of interlocking with said pull-bar for moving said carrier against the force of its springs on the operation of said mechanism, and a trip pin to be controlled by the movement of said carrier arranged at a predetermined point to engage said pull-bar and force the same out of interlocking relation with said pull-bar.

8. In a machine of the character described, 70 the combination with a movably mounted spring retracted carrier including a pull-bar and a plurality of coin-controlled units each commanding a catch-bar, of hand-actuated mechanism including a draw-bar capable of interlocking with said pull-bar for moving said carrier against the force of its springs on the operation of said mechanism, a trip pin to be actuated to engage said pull-bar and force the same out of interlocking relation with said draw-bar, and means adapted to be engaged and actuated by each catch-bar controlling the actuation of said trip pin.

9. In a machine of the character described, 75 the combination with a spring retracted transmission connector including a hooked pull-bar and an actuating mechanism including a hooked draw-bar, of means for holding said pull-bar in position to be interlocked by said draw-bar, and tripping means for forcing said pull-bar out of interlocking relation with said draw-bar, said tripping means being dependent for its action upon the movement of said connector.

10. In a machine of the character described, 80 the combination with a carrier with retractile springs acting thereon and actuating mechanism arranged to be connected by separable connections to the carrier to move it against the force of its springs, of a catch-bar on said carrier, a trip pin to be actuated for effecting the separation of said separable connections, and means arranged to be engaged by said catch-bar controlling the actuation of said trip pin.

11. In a machine of the character described, 85 the combination with a carrier with retractile

5 springs acting thereon and actuating mechanism arranged to be connected by separable connections to the carrier to move it against the force of its springs, of a catch-bar on said carrier, a trip pin to be actuated for effecting the separation of said separable connections, a bell crank actuator positioned for engagement by said catch-bar, and a lift sleeve mounted to receive movement from 10 said bell crank actuator and supporting said trip pin.

12. The combination with a draw-bar and a transmission connector to be drawn thereby, of a pull-bar pivoted to said connector and engageable by said draw-bar to be interlocked therewith, a kick-up pin arranged to contact said pull-bar and force it out of interlocking engagement with said draw-bar, and means for actuating said kick-up pin.

20 13. The combination with a draw-bar and a transmission connector to be drawn thereby, of a pull-bar pivoted to said connector and engageable by said draw-bar to be interlocked therewith, a movable kick-up pin 25 provided with a roller to contact said pull-bar and force it out of interlocking engagement with said draw-bar, and means for supporting and actuating said kick-up pin.

14. In a machine of the character described, 30 consisting of a transmission connector with a pull-bar and a draw-bar arranged to interlock with the pull-bar, a shaft having a lift sleeve thereon, a kick-up pin supported on said sleeve and therewith movable and 35 adapted to contact said pull-bar to force the same out of interlocking engagement with said draw-bar, means for lifting said sleeve, and a key retaining said kick-up pin against rotation.

40 15. In a machine of the character described, consisting of a transmission connector with a pull-bar and a draw-bar arranged to interlock with the pull-bar, a shaft having a sleeve thereon, a bell crank arranged to lift said 45 sleeve, a catch-bar on said connector to be engaged with said bell crank for operating the latter during the movement of said connector, and a kick-up pin movable with said sleeve to contact said pull-bar and force the 50 same out of interlocking engagement with said draw-bar on the operation of said bell crank.

16. In a machine of the character described, 55 consisting of a spring retracted carrier with a pull-bar and a draw-bar arranged to interlock with the pull-bar, a plurality of coin-controlled units supported by said carrier, a shaft having a sleeve thereon, a catch-bar 60 carried by each coin-controlled unit, bell cranks arranged to be engaged and actuated by said catch-bars, a frame for lifting said sleeve commanded by each of said bell cranks, and a kick-up pin movable with said sleeve 65 to contact said pull-bar and force the same

out of interlocking engagement with said draw-bar on the operation of a bell crank.

17. In a machine of the character described, 70 consisting of a spring retracted transmission connector with a pull-bar and a draw-bar arranged to interlock with the pull-bar, a shaft having a sleeve thereon, a bell crank arranged to lift said sleeve, a catch-bar on said connector to be engaged with said bell crank for operating the latter during the movement of said connector, a kick-up pin movable with said sleeve to contact said pull-bar and force the 75 same out of interlocking engagement with said draw-bar, and means for disengaging said catch-bar from said bell crank subsequently to the disestablishment of the interlocking engagement between said pull-bar and draw-bar.

18. In a machine of the character described, 80 consisting of a spring retracted transmission connector with a pull-bar and a draw-bar arranged to interlock with the pull-bar, a shaft having a sleeve thereon, a bell crank arranged to lift said sleeve, a catch-bar on said connector to be engaged with said bell crank for operating the latter during the movement of said connector, a kick-up pin movable with said sleeve to contact said pull-bar and force the 85 same out of interlocking engagement with said draw-bar, and a weight associated with said sleeve for positively repositioning the same along with its actuating bell crank after each operation.

In testimony whereof, I have signed my name to this specification.

CLIFTON W. NIXON.
